UNITED STATES PATENT OFFICE.

NATHAN KASDAN, OF NEW YORK, AND DANIEL POLLACK, OF BROOKLYN, NEW YORK,
ASSIGNORS TO MAJESTIC METAL SPECIALTIES, INC., OF NEW YORK, N. Y., A COR-
PORATION OF NEW YORK.

VANITY BOX.

Application filed August 5, 1924. Serial No. 730,141.

The invention relates to vanity boxes of the character carried by women and comprising a body portion to receive face powder or the like, a lid or cover for said body portion and a mirror, and our invention resides, as to one of its features, in providing the lid or cover with a mirror which shall be exposed at the top of the lid when the box is closed and in so hinging or linking the lid or cover to the body of the box that when the box is open said lid may be faced frontwardly, then standing in an inclined position at the rear portion of the body of the box.

A further feature of our invention resides in a novel container for loose face powder to be seated in the body of the box, this container having a specially formed cover permitting the powder to escape from the container and lodge upon it, and said cover also being adapted as a seat for a powder puff.

The invention will be fully understood from the detailed description hereinafter presented, reference being had to the accompanying drawings, in which:

Fig. 1 is a central vertical longitudinal section, on an enlarged scale, through a vanity box embodying our invention, the section being on the dotted line 1—1 of Fig. 6 and the box being shown in closed condition;

Fig. 2 is a corresponding section through the same, with the lid or cover in open position, and the mirror carried thereby facing frontwardly;

Fig. 3 is a vertical transverse section through the box, taken on the dotted line 3—3 of Fig. 6;

Fig. 4 is a vertical section through a portion of the box, taken on the dotted line 4—4 of Fig. 6;

Fig. 5 is a detached plan view of an interior box, shown in Figs. 1, 2 and 3, within which loose powder, as distinguished from a compact, may be carried;

Fig. 6 is a plan view of the box illustrated in Figs. 1, 2 and 3, and

Fig. 7 is a vertical longitudinal section through a modified form of the invention, a compact being illustrated in the body of the box shown in Fig. 7.

In the drawings, referring to Figs. 1 to

6 inclusive, 10 designates the body of the box and 11 a lid or cover portion for said body. The body portion 10 is circular in outline and has outwardly curved sides 12 and a top opening 13, and the bottom of the body 10 is recessed, as at 14, to receive a box 15 within which toilet powder may be contained, said box 15 being centered in the said recess 14. The box 15 has a cover 16 closely fitting upon the same, as shown in Fig. 2, and said cover has a series of radial grooves or depressions 17 which taper and widen outwardly and terminate at their outer ends in openings 18 through which the powder may sift upon the top of the cover 16, and be more or less confined thereon within said grooves or depressions. Upon the cover 16 will be seated a suitable powder puff or pad 19.

The lid or cover 11 comprises an annular metal ring 20 which is flanged downwardly, as at 21, to enter the open top of the body 10, and said ring in the formation of the flange 21 has formed thereon a shoulder 22 which seats upon the upper edges of the body portion 10 around the opening 13 therein so as to arrest the lid or cover in correct position upon said body 10. The flange 21 has a close friction fit within the edges of the body 10 surrounding the opening 13. The ring 20 is formed with an inwardly extending top annular flange 23 which serves, at its lower surface, as a seat for the edge portion of a mirror 24, which, when the box is closed, faces upwardly and is therefore exposed through the ring 20. The mirror 24 is held firmly in position against the flange 23 by means of a plate 25 which closely fits within the ring 20 and is held in place by an internal shoulder formed in the flange 21 due to the formation of the external shoulder 22.

The lid or cover 11 thus comprises the annular ring 20, mirror 24 and plate 25, and said lid or cover is connected with the body 10 of the box by means of a link 26 which is secured at one end on a pin 27 carried by the plate 25 near the middle thereof and at its outer end on a pin 28 secured to the edge of the body 10 in a recess 29 formed therein. The link 26 is in the form of a reasonably broad flat plate,

and at its inner end is of sleeve formation to enclose the pin 27, while at its outer end said link is also of sleeve formation to enclose the pin 28. The link 26 is formed at its outer end with a right angle bend 30 which permits the link when the box is in closed position to lie within the box, as shown in Fig. 1. The recess 29 at its outer edge forms a shoulder 31 which acts to support the link 26 in an upwardly and rearwardly inclined position, when the box is opened, as shown in Fig. 2.

While the box is in closed position, the lid or cover 11 fully closes the opening 13 in the top of the body portion of the box and at such time the mirror 24 has its face exposed and may be utilized as a mirror without opening the box. When the lid or cover 11 is opened upwardly to expose the powder puff 19 or whatever may be within the body of the box, said lid or cover after being freed from the body of the box will be turned on the pin 27 to carry its rear edge upwardly and its front edge downwardly against the link 26, and in this operation the mirror 24 will be faced forwardly for the convenient use of the owner of the box. One of the special features of our invention resides in the fact that when the box is closed the mirror 24 faces upwardly and may be used without opening the box, and that when the box is opened the lid or cover 11 may be swiveled on the pin 27 so as to face the mirror frontwardly. When the lid or cover 11 has been opened and the mirror is faced forwardly, the lid or cover is supported in inclined position against the link 26, said link being prevented from turning downwardly toward the rear by the engagement of the outer end thereof with the shoulder 31 formed on the body of the box. The link 26 by having some breadth at the pins 27, 28 serves to very firmly connect the lid or cover 11 with the body of the box, and said link permits on the opening of the lid or cover 11 the positioning of the mirror to face frontwardly and also serves as a brace for supporting the mirror in this operative position, as shown in Fig. 2.

The box or container 15 is of special utility when loose powder is to be provided within the vanity box. The grooves or depressions 17 in the top 16 of the container or box 15 gradually widen and deepen toward their outer ends, and in this formation the depressions or grooves 17 may gather enough of the powder from the box for the use of the puff or pad 19 without an undue scattering about of the powder.

The modified form of the invention shown in Fig. 7 utilizes a plain cylindrical body portion 40 and a lid or cover 41 which is substantially identical in construction with

the lid or cover 11 hereinbefore described. In the form of the invention shown in Fig. 7, the lid or cover 41 is equipped with the exposed mirror 42 and back-plate 43, to which the inner end of a link 44 is hinged, 70 the outer end of the link extending outwardly through the rear side of the body 40 and being hinged upon a pin 45. When the lid 41 is released from the body 40 and moved upwardly and toward the rear, said lid may 75 be folded downwardly against the link 44 to face the mirror frontwardly in the manner indicated in Fig. 2. The modified form of the invention shown in Fig. 7 embodies the use of a plain cylindrical box-body 40 80 with no change in the lid or cover 41 and only a slight change in the link 44 adapting said link to the shape of the body 40. In the construction shown in Fig. 7 we illustrate the use of a compact 46 placed within 85 the body 40. Fig. 7 is presented to indicate that we do not limit our invention to all of the small details of form and construction hereinbefore described, since these may be modified without departure from the spirit 90 of our invention.

What we claim as our invention and desire to secure by Letters-Patent, is:—

1. A vanity box comprising a body portion adapted to hold a toilet requisite, a lid or cover portion provided at its top with an outwardly faced exposed mirror and a link connecting said lid or cover portion with said body portion and adapted when the box is open to permit the lid or cover to be turned toward a vertical position to face the mirror forwardly, said link being hinged at one end to said cover portion and at the other end to said body portion.

2. A vanity box comprising a body portion adapted to hold a toilet requisite, a lid or cover portion provided at its top with an outwardly faced exposed mirror and a link connecting said lid or cover portion with said body portion, one end of said link being hinged to the lower side of said lid or cover portion near the center thereof and the other end of said link being hinged to said body portion at one edge thereof, whereby when the box is open said lid may 115 be turned toward a vertical position to face the mirror frontwardly.

3. A vanity box comprising a body portion adapted to hold a toilet requisite, a lid or cover portion provided at its top with an outwardly faced exposed mirror, a link connecting said lid or cover portion with said body portion and adapted when the box is open to permit the lid or cover to be turned toward a vertical position to face the mirror forwardly and means for maintaining said lid or cover in such position, said link being hinged at one end to said cover portion and at the other end to said body portion.

4. A vanity box comprising a body por-

tion adapted to hold a toilet requisite, a lid or cover portion provided at its top with an outwardly faced exposed mirror, a link connecting said lid or cover portion with said body portion, one end of said link being hinged to the lower side of said lid or cover portion near the center thereof and the other end of said link being hinged to said body portion at one edge thereof, whereby when the box is open said lid may be turned toward a vertical position to face the mirror frontwardly and means for maintaining said lid or cover in such position.

5. A vanity box comprising a body portion adapted to hold a toilet requisite, a lid or cover portion provided at its top with an outwardly faced exposed mirror and a link connecting said lid or cover portion with said body portion, one end of said link being hinged to the lower side of said lid or cover portion near the center thereof and the other end of said link being hinged to said body portion at one edge thereof, whereby when the box is open said lid may be turned 10 toward a vertical position to face the mirror frontwardly, said link being formed on its ends with sleeves and said lid or cover portion and said body portion having pins engaged by said sleeves.

15. A vanity box comprising a body portion adapted to hold a toilet requisite, a lid or cover portion provided at its top with an outwardly faced exposed mirror and a link connecting said lid or cover portion with said body portion, one end of said link being hinged to the lower side of said lid or cover portion near the center thereof and the other end of said link being hinged to said body portion at one edge thereof, whereby when the box is open said lid may be turned 20 toward a vertical position to face the mirror frontwardly, said link being formed on its ends with sleeves and said lid or cover portion and said body portion having pins engaged by said sleeves, and said body portion 25 having a shoulder to be engaged by said link in the open position of the box to brace said link and the lid or cover portion connected therewith.

25. A vanity box comprising a body portion adapted to hold a toilet requisite, a lid or cover portion provided at its top with an outwardly faced exposed mirror and a link connecting said lid or cover portion with said body portion, one end of said link being hinged to the lower side of said lid or cover portion near the center thereof and the other end of said link being hinged to said body portion at one edge thereof, whereby when the box is open said lid may be turned 30 toward a vertical position to face the mirror frontwardly, said link being formed on its ends with sleeves and said lid or cover portion and said body portion having pins engaged by said sleeves.

portion and said body portion having pins engaged by said sleeves.

6. A vanity box comprising a body portion adapted to hold a toilet requisite, a lid or cover portion provided at its top with an outwardly faced exposed mirror and a link connecting said lid or cover portion with said body portion, one end of said link being hinged to the lower side of said lid or cover portion near the center thereof and the other end of said link being hinged to said body portion at one edge thereof, whereby when the box is open said lid may be turned 35 toward a vertical position to face the mirror frontwardly, said link being formed on its ends with sleeves and said lid or cover portion and said body portion having pins engaged by said sleeves, and said body portion 40 having a shoulder to be engaged by said link in the open position of the box to brace said link and the lid or cover portion connected therewith.

Signed at New York city, in the county 50 and State of New York, this 2nd day of August, 1924.
